J. B. BUCKLEY

COMBINATION GAME BOARD AND SCORE COUNTER

Filed Feb. 20, 1928

FIG. 1-

FIG. 2-

Inventor

J. B. Buckley

By *Francis C. Buckley*

Attorney

UNITED STATES PATENT OFFICE.

JOSEPH B. BUCKLEY, OF DETROIT, MICHIGAN.

COMBINATION GAME BOARD AND SCORE COUNTER.

Application filed February 20, 1928. Serial No. 255,788.

This invention relates to new and useful improvements in games and particularly to game-boards.

One object of the present invention is to provide a device of this character which may be used to play a game, or may be used to keep a record of the plays, and the scores, of the opposing teams, when watching the actual game, or while listening to the game as broadcast over the radio.

Another object is to provide a device of this character by means of which a game may be played, and at the same time, each player may keep his own score.

Other objects and advantages will be apparent from the following description when taken in connection with the accompanying drawing.

In the drawing:

20 Figure 1 is a plan view of the combined game-board and score keeper.

Figure 2 is an enlarged vertical sectional detail view on the line 2—2 of Figure 1.

Referring particularly to the accompanying drawing, 10 represents a board, which forms the base of the device, the same being provided with pairs of slots 11, through which are adapted to be passed the ends of strips of paper, or the like, 12, having thereon the names of the opposing teams of the game. Mounted on the board, adjacent one end thereof, is a disk 13, on which are printed the circular series of marks 14, representing yards, as in the game of football. The said marks are numbered from points adjacent the lower edge of the disk, beginning with "1", and proceeding around the disk, in opposite directions, toward the upper edge thereof, where such numbering terminates at 40 "50". The disk is held against rotation by the central pin 15, and the pin 16, which is disposed through a projection 17, on the lower edge portion of the disk, and through the base board 10. On the central pin 15 is mounted 45 an indicating hand 18, having an arrow 19 on one end for traversing the marks on the edge of the disk. Disposed behind the disk 13, are similarly shaped disks 20 and 21, said disks being held against rotation by the pins 50 15 and 16. Mounted on the central pin, between the disk 13 and the disk 20, is an arm 22 which projects beyond the edge of the disk 13, and is marked "10 yards", the said projecting end portion of the arm being of a 55 width equal to ten of the marks on the disk 13, representing ten yards. Mounted on the

pin 15, between the disks 20 and 21, is an arm 23, the outer end of which projects beyond the periphery of the disk 13 and is marked "Home score". A similar arm 24 is mounted 60 on the pin 15, between the disk 21 and the base-board, and projects beyond the periphery of the disk 13. It will be noted that the arm 23 projects beyond the right-hand side of the disk 13, while the arm 24 projects beyond the left-hand side thereof, said arm 24 having its projecting end marked "Visitor's score". This arrangement of the arms between the disks, serves to prevent interference 65 of the arms, when they are swung around on the central pivot pin 15, each arm being readily movable around the disk. The zero points on the disk 13 are marked, respectively "Visitor's goal" and "Home goal".

Adjacent the other end of the base-board 75 there is mounted a spinner 25, which is adapted to traverse a dial 26, having legends printed thereon, representing gains or losses, in yards, and scoring plays in the game.

In the use of the device as a game, one of 80 the two players takes the board, and after having set the arms 22 and 24 at the respective zero points of the disk 13, the pointer 18 so that its arrow 19 registers with the "50" on said disk, and the outer end of the 85 arm 23 set so that its left-hand edge registers with "50", and the right-hand edge registers with the "40" of the disk, he rotates the spinner 25. Should the spinner stop on the space of the disk 26, marked "15 yd. 90 gain", he moves the hand 18 so that the arrow 19 points to the mark fifteen points, to the right of the "50", which would be thirty-five (35). The player has four spins of the spinner 25, representing the four 95 downs in the game of football, and each time that the spinner stops, the player moves the hand 18 to the right, for gains, and toward the left, for losses. If the hand 18 is advance up to, or beyond the edge of the arm 100 22, which lies on the "40", such arm is moved to the same mark on which the pointer 18 lies, and the board is yielded to the other player. At the same time, the previous player moves his score arm around the disk 13 105 to the proper mark indicating the points scored during his play. When, however, a "touchdown" or a "field goal" is made by a player, by means of the spinner 25, the indicating arms, except for the score arms 23 110 and 24, are reset to their original positions at the beginning of the play. The other play-

er proceeds in the same manner as the first player, by moving the hand 18 in accordance with the gains or losses shown on the dial 26, of the spinner, in his four downs. This is continued until one of the players has moved the hand 18 around to the zero or goal point on the disk, or has scored forty (40) points.

The device is also adapted to be used for 10 keeping the score of a game being watched, or listened to over the radio. The watcher or listener sets the arms as in playing the game, and places the arm 22 to the right or left of the "50", according to the side which has the 15 ball. He then moves the hand 18 as the plays are seen or given by the announcer over the radio.

It will, of course, be understood that while I have illustrated the game-board as adapted 20 for playing or keeping the score of a football game, the board may be used for other games by slight modifications in the markings on the dials and indicating arms and hands.

25 What is claimed is:

1. A combined game-board and score-keeper comprising a base, a dial fixed on the base having duplicate marks ranging therearound representing in one instance yards of gain 30 and loss of the players and in the other instance as points scored in the game by the players, an indicator adapted to be moved around the dial in accordance with the readings of a spinner or the like, and separate indicators for the players movable around the 35

periphery of the dial in connection with said marks when used as game points.

2. A combined game-board and score-keeper comprising a base, a dial fixed on the base and having marks indicating gains and 40 losses of the players ranging around the dial in opposite directions from a given point, an indicating hand mounted for traversing the dial marks in one direction for one player and in the other direction for the other player, an indicator for movement around the periphery of the dial in either direction from said given point, and independent indicators movable around the periphery of the dial at opposite sides of said given point 50 for recording the points scored by the players.

3. A combined game-board and score-keeper comprising a base, a dial on the base having play indicating marks ranging there- 55 around in opposite directions from a given point for the players, an indicator arranged to be moved around the dial in either direction for indicating gains and losses of the players, a second indicator movable around 60 the dial in one direction for recording the gains and losses of one player, and movable in the other direction for recording the gains and losses of the other player, and separate indicators for the players movable around 65 the periphery of the dial for recording the scores of the players.

In testimony whereof, I affix my signature.

JOSEPH B. BUCKLEY.
